UNITED STATES PATENT OFFICE.

CHARLES PHILIPPE CHOQUETTE AND ANTOINE MOÏSE MORIN, OF ST. HYACINTHE, CANADA.

ACETYLENE-GAS GENERATOR.

SPECIFICATION forming part of Letters Patent No. 595,451, dated December 14, 1897.

Application filed June 11, 1896. Serial No. 595,184. (No model.) Patented in England June 13, 1896, No. 13,115; in France June 20, 1896, No. 244,818, and in Canada February 12, 1897, No. 54,976.

To all whom it may concern:

Be it known that we, CHARLES PHILIPPE CHOQUETTE and ANTOINE MOÏSE MORIN, citizens of the Dominion of Canada, residing at 5 the town of St. Hyacinthe, in the county of St. Hyacinthe and Province of Quebec, Canada, have invented certain new and useful Improvements in Acetylene-Generators; and we do hereby declare the following to be a full, 10 clear, and exact description of the invention, such as will enable others skilled in the art to which it appertains to make and use the same.

Patents for this invention have been obtained as follows: In England, No. 13,115, 15 dated June 13, 1896; in France, No. 244,818, dated June 20, 1896, and in Canada, No. 54,976, dated February 12, 1897.

Our invention has reference to an automatic generator—that is, one in which the production 20 of the gas is automatically regulated; and it consists in the novel construction and combination of the parts hereinafter fully described and claimed.

The object of our invention is to provide an 25 acetylene-generator that once started will demand no attention further than keeping the supply of water at about the same level and removing the residue of the decomposition, as well as supplying the carbid of calcium 30 when needed, the production of gas being automatically regulated, as shown hereinafter.

The drawing shows a vertical section of our generator and, as can be seen, is composed of an outer tank A, having a bottom *a*, but no 35 top, and into which is placed another tank or holder B, having no bottom, but whose top is formed by means of a separate chamber C, whose bottom portion C' is funnel-shaped and is provided with a circular opening at C² just 40 large enough to smoothly slide along the rod D. This vessel or chamber C is also provided with the guide C³ or any other suitable substitute, so that when the tank B rises it always occupies the same position in the tank A.

45 Now to put the apparatus in operation water is poured into the bottom of the tank A, by means of the tube *a'* or otherwise, until the required level is reached, which can be seen by a suitable water-gage *a'*. However, 50 in doing this the air contained in the vessel

B is compressed, so that by opening a valve placed on the outlet-pipe C⁴ (not shown on the drawing) this air escapes by passing through the pipe C⁵, which is provided with a check-valve, (not shown on the drawing,) so as to 55 allow no vapor of water to get into the chamber C. This being done and a certain amount of pulverized or granulated carbid of calcium being put into the funnel C', when held up by means of the rings K or otherwise, through 60 the opening E, which is closed by a suitable stopper, the operation at once begins on unhooking the rings K, for then a certain amount falls down through the opening C², which, when the tank B is down, as shown on the 65 drawing, is opposite the conical end *d* of the rod D and is consequently open. However, as the production of gas takes place the pressure in the tank B runs up, and when the production is more than the demand the pressure 70 runs up enough to force the water up between the tanks A and B, as shown, and at a given moment raises the tank B. However, when this happens the opening C² comes opposite the cylindrical portion of the rod or stopper 75 D, and no more carbid of calcium is supplied, thus stopping all production of gas, for as the chemical is put into the water when in a highly subdivided state its decomposition is almost instantaneous on reaching the water, so that 80 the stopping of the supply stops the production of the acetylene. As the gas passes out through the pipe C⁵ into the chamber C, and from thence to the point of consumption through the pipe C⁴, it comes into contact with 85 the pulverized carbid of calcium F and is thus completely dried of all its entrained water, as the carbid of calcium is highly hygroscopic. When the pressure runs down, the tank B falls, and again the carbid of calcium 90 pours down through the opening C² as it comes opposite the cone *d*, and a new quantity of gas is made, the operation continuing as before.

The rod or stopper D is held in position by any suitable means; but it is joined to the 95 bottom of the tank A by means of a small rod *d'*, passing through the bottom *a*, where it is provided with a thumb-screw *d''*, so as to regulate the height of the rod or stopper D. This small rod *d'* is also provided with a shoulder 100

*d*³, against which abuts a cross-piece *b*, which slides over it and thus prevents further upward movement of the tank *B*. This can also be done by means of hooks *H*, or, in fact, by 5 any convenient device.

As can be seen, the water and carbid of calcium being in separate vessels the chemical is not mixed up with the residue of the decomposition and the water.

10 The top of the apparatus is made heavy enough to maintain a suitable pressure in the holder *B* when the provision of the pulverized or granulated carbid of calcium is about run out.

15 Having described our invention, what we claim, and desire to secure by Letters Patent, is—

In an acetylene-gas generator, the combination, of an outer tank to contain water in 20 the bottom, means for introducing this water, a small rod *d'* surmounted by a larger rod or stopper *D* having its point of junction with the rod *d'* conical in shape, means for regu-

lating the length of the whole, and secured to its bottom, and means for regulating the amount of rise of the inner tank with an inward tank or holder having its top formed by means of a tank or chamber to contain the pulverized or granulated carbid of calcium, and having a funnel-shaped bottom provided with an opening at its lower extremity, of just sufficient size to freely slide over the rod or stopper *D*, means of introducing the carbid of calcium into the funnel-shaped chamber, means for the escape of the gas to the point of consumption, and means to guide the inward tank or holder into the outward tank, substantially as described, and for the purposes set forth.

In testimony whereof we have affixed our 4 signatures in presence of two witnesses.

CHARLES PHILIPPE CHOQUETTE.
ANTOINE MOÏSE MORIN.
